UNITED STATES PATENT OFFICE.

CHARLES L. MOHR, OF CHICAGO, ILLINOIS, ASSIGNOR TO MOHR LINO-SAW COMPANY,
OF CHICAGO, ILLINOIS, A CORPORATION OF ILLINOIS.

PRINTING-SLUG-SAWING DEVICE.

1,281,807.

Specification of Letters Patent. Patented Oct. 15, 1918.

Original application filed March 16, 1914, Serial No. 825,049. Divided and this application filed February 4, 1918. Serial No. 215,287.

To all whom it may concern:

Be it known that I, CHARLES L. MOHR, a citizen of the United States, and a resident of Chicago, county of Cook, and State of Illinois, have invented certain new and useful Improvements in Printing-Slug-Sawing Devices, of which the following is a specification.

My invention relates to improvements in attachments for linotype machines and has especial reference to improvements in means for sawing linotype slugs or type bars as they are ejected from the machine.

The subject matter of this application was first disclosed in my co-pending application for Letters Patent of the United States on linotype machines, Serial No. 825,049, filed March 16, 1914, and this application is in the nature of a division of said co-pending application.

The objects of my invention are to facilitate the repair and replacement of the rotary saw which forms a primary feature in my improved linotype machine as described and claimed in said co-pending application; to provide means whereby the saw which is substantially completely incased when operating, may be readily and easily examined and removed either for sharpening or for replacement by another saw.

My invention consists in the combination with a linotype machine of a rotary saw related to the path of the linotype slugs as they are ejected, the saw being mounted upon one end of a saw arbor and completely incased when in operating condition, and the opposite end of the shaft rotatably mounted in a pivotally mounted bearing so that the saw end of the shaft can be readily swung out from the machine for inspection and removal of the saw.

My invention also consists in the several features of construction and in the arrangements and combinations of parts by means of which I am enabled to attain the above mentioned and other objects and all as hereinafter described and particularly pointed out in the appended claims.

My invention will be more readily understood by reference to the accompanying drawings forming a part of this specification and in which:

Figure 1 is a fragmentary side elevation partly in section of the front portion of the

linotype slug forming part of a linotype machine;

Fig. 2 is a side elevation of the saw shaft showing the upper supporting bearing in section;

Fig. 3 is a horizontal section on the line 3—3 of Fig. 2;

Fig. 4 is a horizontal section on the line 4—4 of Fig. 2; and

Fig. 5 is a fragmentary vertical section of the lower end of the saw arbor on the line 5—5 of Fig. 2.

In said drawings 1 represents a mold wheel of a linotype machine partly broken away to show the ejector 2. In front of the ejecting position is arranged the usual slug trimming or sizing mechanism 3 and in front of the trimming mechanism I provide a substantially closed casing consisting of a lower relatively fixed part 4 and an upper removable part 5 secured to and upon the lower part by the cap screws 5'. Within the casing I provide a circular saw 6 mounted upon the lower end of the vertical saw shaft or arbor 7. The shaft is movable vertically to permit the vertical adjustment of the saw 6 relatively to the mold slots for cutting the slugs at various points. For this purpose I provide a sleeve 8 at the upper end of the shaft through which the shaft freely slides, and I so mount the sleeve 85 that while it is free to turn with the shaft 7, it is held against vertical movement. The mounting which I provide also permits the shaft to be tipped or to be swung about as upon a universal joint to facilitate the inspection and repair or removal of the saw.

While the lower part 4 of the saw casing is movable vertically with the saw it is so mounted upon the frame of the linotype machine that it cannot be readily removed, and it is not necessary to remove it for the inspection, repair or removal of the saw 6.

I provide the shaft 7 with a longitudinal key slot 9, and I provide a key 10 fixed in the sleeve 8 and fitting the slot 9. By this means the shaft is slidable through the sleeve but they are secured to rotate together.

The sleeve extends above and below a bracket 11 fixed upon or carried by the frame of the linotype machine. Upon the upper end of the sleeve I secure a fly wheel 12, and upon its lower end a belt pulley 13,

This pulley is adapted to be belted to a driving pulley 14 on a driving shaft 15, which in turn is adapted to be driven at relatively high speed by means not shown.

5 I provide a bearing ring 16 surrounding the middle portion of the sleeve 8 which ring normally lies horizontal in the bracket 11, and between the ring 16 and sleeve 8 I arrange a circumferential row of anti-friction bearing balls 17 which permit the free rotation of the sleeve 8 within the ring 16.

10 The sleeve 8 is provided with a fixed ring 18 which lies within the ring of balls 17 and this ring 18 and the bearing ring 16 are provided with opposed ball grooves whereby the 15 balls act to lock the two rings against relative movement longitudinally of the shaft 7.

I form the outer surface 19 of the ring 16 as a section of a sphere, the center of the 20 sphere lying at the center of the shaft 7 and midway between the upper and lower surfaces of the ring; and I provide an outer fixed ring 20 mounted in the bracket 11 and having an inner spherical surface 21 25 within which the ring 18 nicely fits.

This construction mounts the upper end of the saw arbor in a bearing through which the saw shaft can slide longitudinally, by which it can be rotated and upon which the 30 shaft can be tipped about as upon a universal joint or bearing, as indicated in dotted lines in Figs. 1 and 2.

I provide the lower end of the shaft 7 with a fixed collar 22 and a central longitudinally projecting saw mandrel or pin 23. The saw is provided with a central hole fitting the pin 23, and I hold the saw tightly against the under side of the collar 22 by means of a center locking screw or 40 bolt 24 which is screwed into a center threaded opening in the lower end of the pin 23. I provide a washer 25 between the head of the screw and the end of the pin, and between the washer and the saw I arrange first a large washer 26 contacting 45 with the saw and then the inner ring 27 of a combined circumferential and end thrust bearing which is completed by the outer ring 28 and the annular ring of anti-friction balls 29. Each of the rings 27 and 50 28 is provided with an annular groove to receive the balls 27 which hold the two rings against relative movement longitudinal of the shaft. The bearing as a 55 whole is located to the shaft by the bolt 24.

The outer ring 28 of the bearing is received in an opening 30 which I provide for it in the lower part 4 of the saw casing. Although I provide such a close fit for the 60 ring 28 in the socket 30 that once the bearing has been mounted in the lower part 4 of the saw casing it will not be free to rise therein, as a measure of safety, I provide an interior shoulder 31 on the upper part 65 of the casing surrounding the shaft and

adapted to contact, when the casing is closed, with the upper face of the collar 22 and prevent the relative rising of the shaft.

It will now be clear that any vertical adjustment of the saw casing will carry the saw with it, the upper end being freely movable through the upper bearing.

When the machine is in operation and it becomes necessary to remove the saw from the casing, and, as often happens, to remove the saw shaft from the machine, it is only necessary to remove the cap screws 5' which secure the upper part or cap of the saw casing in place, slide this part up 80 the saw shaft, as shown in dotted lines in Fig. 1, and then lift the shaft 7 vertically to free the saw and the lower bearing from the lower part 4 of the saw casing.

Having freed the saw from the lower part 85 of the casing, the shaft 7 can then be tipped or swung forward away from the lower part of the casing, the upper spherical bearing mounting permitting this action, and when the saw is clear of the casing, as shown in 90 Fig. 1 in dotted lines, the saw shaft and saw can be drawn downwardly out of the bearing past the lower part of the casing and I am thus enabled to entirely remove the saw shaft and saw from the machine. 95

The shaft being out it is a simple matter to either repair the saw 6 or remove it and substitute another and the remounting of the saw ready for use again can likewise be easily and quickly accomplished. 100

By means of my invention I am enabled not only to conserve the time of the operator and of the machine itself but the workman is also enabled easily to keep his product up to a high degree of accuracy, for the reason that if it is a difficult problem to remove or repair the saw the workman naturally puts off the repair or replacement of same until the product reaches its absolute limit of inaccuracy. 110

As many modifications of my invention will naturally suggest themselves to one skilled in the art, I do not limit my invention to the structures illustrated except as defined in the appended claims. 115

I claim:

1. The improvement herein described comprising a saw arbor, a saw mounted within a substantially closed casing and upon the one end of said saw arbor, a bearing within said casing upon which the said end of the saw arbor is mounted, a bearing for the opposite end of said arbor, through which said arbor can slide endwise, and a universal connection between said second mentioned bearing and a fixed bracket whereby when the saw end of the arbor is free of said casing the arbor can be tipped or inclined as upon a universal joint. 120

2. In a linotype machine provided with 130

- a mold for casting slugs and an ejector for forcing the slugs out of the mold, a saw arranged in the path of the slugs, as they are ejected, for cutting the slugs, an arbor 5 upon one end of which the saw is mounted, a bearing carried by the machine for the saw end of the arbor, a bearing carried by the machine for the opposite or driving end of the arbor, the arbor being movable through 10 the said driving end bearing, a spherical joint between said driving end bearing and the machine whereby when the saw end of the arbor is freed from contact with the machine the arbor can be inclined to permit 15 the saw to pass the bearing at the saw end as the arbor is drawn out of the bearing at the driving end.
3. In a linotype machine having a mold for casting a slug and an ejector for forcing the slug out of the mold, a saw mounted in the path of the slug for cutting it in two as it is ejected, an arbor upon one end of which the saw is secured, a casing carried 20 upon the machine and within which the saw is inclosed; a relatively fixed bearing carried by the machine for the other end of said arbor, the arbor being movable through said fixed bearing, a spherical joint between the 25 fixed bearing and the machine whereby when the saw end of said arbor is free of said casing the arbor can be inclined in the fixed bearing to permit the saw to freely pass said casing as the arbor is withdrawn from said fixed bearing.
4. In a linotype machine having a slot 35 through which a type slug is ejected, a saw for cutting the slug as it is ejected, a casing inclosing the saw, an arbor upon one end of which the saw is fixed for rotation therewith, a bearing within the casing for the saw 40 end of the arbor, a bearing carried by the machine for the opposite end of the arbor, a sleeve within said bearing and within which the arbor is movable longitudinally, driving connection between the sleeve and the arbor, 45 a belt pulley on one end of said sleeve, a universal joint connection between the bearing surrounding the sleeve and the machine whereby the arbor can be inclined relatively to the machine when the saw is free of said 50 casing, as and for the purpose specified.

In testimony whereof, I have hereunto set my hand this 2 day of February, A. D. 1918.

CHARLES L. MOHR.
